[57] CLAIM

The ornamental design for the telephone, as shown and described.

DESCRIPTION

FIG. 1 is a left side, top and right side perspective view of a telephone showing my new design;

FIG. 2 is a top plan view thereof;

FIG. 3 is a bottom plan view thereof;

FIGS. 4 and 5 are respectively right and left side elevational views thereof;

FIGS. 6 and 7 are respectively elevational views of the sides opposite to FIG. 4 and to FIG. 5; and

FIG. 8 is a top perspective view of a second embodiment thereof, the sole difference being the showing of numbers rather than pushbuttons.

FIG. 1

FIG. 4

FIG. 5

FIG. 2

FIG. 3

FIG. 6

FIG. 7

FIG. 8
